UNITED STATES PATENT OFFICE.

WALTER H. BREMER, OF KANSAS CITY, MISSOURI.

DESIGN FOR AN ICE-PICK HOLDER.

48,966.

Specification for Design.

Patented May 2, 1916.

Application filed February 7, 1916. Serial No. 76,866. Term of patent 14 years.

To all whom it may concern:

Be it known that I, WALTER H. BREMER, a citizen of the United States, residing at Kansas City, in the county of Jackson and State of Missouri, have invented a new, original, and ornamental Design for Ice-Pick Holders, of which the following is a specification, reference being had to the accompanying drawing, in which:

Figure 1 is a perspective view of an ice

pick holder illustrating my new design. Fig. 2 is a front elevation of the design. Fig. 3 is a side elevation of the design.

I claim:

The ornamental design for an ice pick holder, as shown.

WALTER H. BREMER.

Witnesses:

F. G. FISCHER,

L. J. FISCHER.
